UNITED STATES PATENT OFFICE.

EUGENE PRINGLE, OF GLOVERSVILLE, NEW YORK.

BREECH-LOADING GUN.

SPECIFICATION forming part of Letters Patent No. 439,895, dated November 4, 1890.

Application filed March 8, 1890. Serial No. 343,199. (No model.)

To all whom it may concern:

Be it known that I, EUGENE PRINGLE, a citizen of the United States, residing at Gloversville, in the county of Fulton and State 5 of New York, have invented certain new and useful Improvements in Fire-Arms, of which the following is a specification.

My invention relates to improvements in that class of fire-arms known as "breech-loading;" and it consists in the combination 10 of parts and devices hereinafter described, and specifically set forth in the claims.

The objects of this invention are, primarily, to provide in breech-loading fire-arm mechanisms, by which the operation of parts will be advantageously improved and made more efficient; and, secondarily, to provide a combination 15 of devices and elements whereby the improvements in this invention can be embodied 20 in fire-arms.

In the drawings forming a part of this specification, Figure 1 is a sectional view of the stock, barrel, receiver, movable breech-block, finger-lever, and operating mechanism of the 25 fire-arm. Fig. 2 is a view of the receiver from its lower side with the fore-arm plate in place with the same. Fig. 3 is a sectional view of the stock, barrel, receiver, movable breech-block, and finger-lever, with the latter two 30 thrown down and away from the stock, and illustrates the manner in which the extractor is operated and the hammer is set at half-cock. Fig. 4 is a sectional view of the stock, barrel, receiver, breech-block, and finger-lever 35 in place for firing, and illustrates the operating lock mechanism provided with double setting triggers. Fig. 5 is a cross-sectional view taken at line 1 in Fig. 4, and looking toward the muzzle of the fire-arm. Fig. 6 is a view, part 40 in section, taken in line 2 in Fig. 4, and looking toward the stock. Fig. 7 is an elevation showing the part of the receiver broken away and exposing a side of the movable breech-block, to which the working mechanism is attached, 45 and illustrating the same by dotted lines and showing the extractor by full lines. Fig. 8 is a sectional view taken at line 3 in Fig. 1, and shows the barrel-wrench lever or arm thrown down preparatory to revolving the barrel. 50 Fig. 9 is a side elevation of the hammer. Fig. 10 is a view of the same from its rear side.

Fig. 11 is a side view of the fly. Fig. 12 is a rear side view of the same. Fig. 13 is a perspective view of the elastic keeper for holding the movable breech-block in place. Fig. 55 14 is a plan view of the trigger-plate, double-set triggers, and their springs. Fig. 15 is a rear end view of the same taken at line 4 in Fig. 14.

The same letters of reference refer to similar parts throughout the several views.

In the drawings, A is a stock of the fire-arm.

B is the barrel.

C is the receiver (or frame) which holds the latter secure to the former and receives the 65 movable breech-block and its operating mechanism.

D is the movable breech-block, and E is the finger-lever, secured to the said breech-block and having the trigger-guard integral with it. 70

The screw-threaded socket C' is integral with the receiver C, and has its screw-threads preferably made with a square form, although they may be made V shape. The rear end portion of barrel B has integral with it the 75 screw-threaded stem b, having screw-threads corresponding with the screw-threads of the socket C'. Secured to the lower side of the barrel B and neighboring the screw-threaded stem b is the lug F, which lug can 80 be integral with the barrel or attached to it in a secure manner so as to have a secure and strong holding with the same without liability of its moving; yet I prefer to secure this lug to the said barrel by a dovetail form 85 of connection consisting of tenon made with said lug and a dovetail socket in the lower side of the barrel, substantially as shown in Figs. 1, 3, 4, and 8. Secured to this lug F by means of the pivot-pin f is a lever or arm 90 G. The head end of this lever or arm is preferably provided with ears g g, through which the pivot-pin f passes, to hold it secured to the said lug F. This lever being thus pivoted can be turned to position parallel with the lower side of the barrel, as shown by full lines in Figs. 1, 3, and 4, and at will it may be turned to position of dotted lines in Fig. 1 and full lines in Fig. 8. When this lever is in position at an angle with the barrel, as shown by dotted lines in Fig. 1 and by 100 full lines in Fig. 8, it may be employed for

revolving the barrel in either direction, as for screwing its screw-threaded stem *b* into the screw-threaded socket *C'* or the reverse.

The ears *g g* of the lever *G* are made of a length sufficient to project past the rear side of the lug *F* to a distance of an eighth of an inch, (more or less), so that when the said lever is in horizontal position, as shown in Fig. 1, the ends of ears *g* will project rearwardly past the said lug and enter into the recess *a*, provided in the receiver *C*, with their outer sides bearing against the sides of the said recess *a*, when the barrel will be secured from turning in either direction. When lever is thrown from position of full lines in Fig. 1 to that of dotted lines in the same figure and to full lines in Fig. 8, the said projected portions of the ears *g g* of said lever will be thrown out of engagement with the sides of the recess *a* of the receiver *C* and be so unlocked as to allow the barrel *B* to be unscrewed out of socket *C'*.

G' is the fore-arm, which is secured to the barrel *B* by any known holding device, as by a screw or pin. (Not shown.) This fore-arm has secured to it the fore-arm plate *H*, and has in its rearward portion and in its side neighboring the barrel *B* the recess *G²* for receiving the lever *G* when in position of full lines in Fig. 1.

The fore-arm plate *H* is extended rearward of the rear end of the fore-arm *G'* to a distance sufficient to close the opening in the receiver between the forward end of the finger-lever 35 and the rear end of the fore-arm. With this extended portion of plate *H* are made the tongues *h*, which work in the grooves *h'*, made in the sides of the receiver *C*, as shown in Fig. 8. By the employment of these tongues 40 *h* with said grooves *h'* the rear end of the fore-arm may be readily and securely locked with both the receiver and the barrel. When the lever *G* is to be moved from full lines to dotted lines in Fig. 1, preparatory for removing the barrel from the receiver, the screw or pin or other device (not shown) which may be used to secure the forward portion of the fore-arm with the barrel will be removed. The fore-arm will then be moved forwardly, so as 45 to draw the tongues *h* from out of grooves *h'*, when the fore-arm will be detached from the barrel, so as to give access to lever *G*, which lever can then at will be turned down from position of full lines in Fig. 1 to that of dotted lines in the same figure, and as shown in 50 Fig. 8, for use as a wrench lever or arm for revolving the barrel.

The finger-lever *E* is securely fastened by pins or screws *d d* to the movable breech-block *D*, which latter is chambered to receive within it the hammer *I* and its sear *I'* and spring *i*. The finger-lever *E* is suitable recessed to receive the trigger *K* or double triggers *K K'*, or a suitable trigger-plate holding 65 the said trigger or triggers, and with which plate they may be pivoted by pins *t*. The movable breech-block being secured to the

finger-lever *E*, the hammer *I* and sear *I'*, pivoted to the former, are held in proper relation to the trigger or triggers pivoted with 70 the latter, and these parts will be so assembled together that when the finger-lever is moved downwardly from the stock and forwardly toward the fore-arm and from position shown in Figs. 1 and 4 to that shown in 75 Fig. 3, the entire operating mechanism between the trigger-guard and rear end of barrel *B*, including the firing-pin, hammer, and its sear and trigger, will be carried out from the chamber of the receiver *C* and fully uncover or unclose the rear open end of the barrel of the fire-arm, so as to allow the operator to remove the shell of the exploded cartridge or introduce a cartridge within the cartridge-chamber of the barrel of the arm. 80

The movable breech-block *D* is pivoted to the receiver *C* by pivot-pin *L*, secured in the side portions of the said receiver, as shown in Figs. 1, 3, 4, and 5. The pivot-hole *D'* of this movable breech-block is made with an oblong 90 form and with a width equal to the diameter of the pivot-pin *L* and with a length about one-half greater (more or less) than the diameter of said pivot-pin. This oblong pivot-hole *D'* is so located in relation to the said pivot-pin *L* and the elastic keeper *M*, bearing against the front end of the said breech-block, that when the latter is in place in the receiver *C*, as in Figs. 1 and 4, the pivot-pin *L* will occupy the forward portion of the oblong pivot-hole 100 *D'*, as shown, while the said keeper will permit the breech-block to be readily moved forward to a short distance, so as to allow the inclines *e* made with the breech-block *D* to disengage from inclines *c* made with the receiver, (shown by full lines in Fig. 7,) and the incline *e* of the breech-block to disengage with incline *c*, also made with the receiver. Any suitable mechanism can be employed for holding the said movable breech-block 110 crowded rearwardly against the rear portions of the receiver; yet I prefer to employ the elastic keeper *M*, Figs. 1, 3, and 4, secured within the forward portion of the chamber of the receiver, and having one or more elastic 115 limbs bearing on the forward end portion of the breech-block *D*, or a piece secured to the finger-lever *E*. This keeper is shown in Fig. 13 to be made with elastic arms *m m*, which have bearings on the points of the forwardly-inclined ends *n' n'*, Figs. 1, 3, 4, and 6, of the sides of the breech-block *D*. The breech-block *D* is shown to have with it the incline *e*, which engages with the inclines *c*, made with the rear end wall of the receiver *C*, yet 125 this incline *e* can be made with the finger-lever or any suitable piece secured to said finger-lever, if preferred. The surfaces *e'* and *c'*, provided, respectively, with the breech-block and receiver, are substantially corresponding inclines in relation to a radial line drawn from the center of the pivot *L* (on which the breech-block turns) to the lower terminations of said surfaces, as broken lines 130

in Figs. 3 and 4, and when the breech-block D is held crowded rearwardly against the rear end wall of the receiver the said incline e' and c' will coact to hold the said breech-block 5 securely in place and tightly closing the rear end of the chamber of the barrel B.

Pivoted on the pivot-pin L is the extractor O, having its arm working within a suitable recess made in the movable breech-block and its 10 head end portion working in a suitable recess made in the rear end portion of the barrel, as illustrated in Figs. 5 and 7. This extractor has made with its lower end portion and neighboring the pivot on which it moves, the step 15 o , which projects forward of the circular pivot end of said extractor and is also provided with a second step o' , which latter projects relatively forward of the curve of the first step o , as illustrated in Fig. 7 by full lines, and 20 by dotted lines in Figs. 1, 3, and 4. Made in the movable breech-block, at a point neighboring the pivot L and relatively forward of the center of the same, is the recess a , of size and form substantially corresponding with 25 that of the step o . When the movable breech-block is being thrown down toward position of full lines in Fig. 3, the inclines e c and e c will by their coaction move the said breech-block relatively forward, so that its oblong 30 pivot-hole D will be carried forwardly until the pivot-pin L occupies the rearward portion of said hole, as shown in said Fig. 3, and at the same time the recess a will be carried upwardly to receive the step or projection o , (on 35 the pivoted end of the piece or extractor O,) when the breech-block will be keyed or locked from moving back or down, and will be so held until the breech-block has again been swung back into the chamber of the receiver. 40 When the forward swinging movement of the breech-block is continued, the forward projections n n of said breech-block will be carried against the step o' , made with the piece or extractor O, and swing the said extractor 45 rearwardly on its pivot, when the extractor, with its engaging lip engaging with the rim of the shell (not shown) in the chamber of the barrel, will withdraw the shell of the cartridge, so that it can be readily removed by the operator. 50 A reverse movement of the finger-lever will return all the said parts to their normal positions.

I is the hammer suitably pivoted within the chamber of the movable breech-block, 55 and is provided with half and full cock notches p p' for engagement with the sear I'. This hammer is also provided with the step P, which is projected relatively forward of the pivot on which the said hammer moves, 60 and with a second forwardly-projected portion P'. (Shown by full lines in Figs. 1, 3, and 4, and by dotted lines P', Fig. 1.)

Q is the mainspring which actuates the hammer. This mainspring has its forward 65 end secured within the forward portion of the chamber of the receiver, preferably by a screw, and has its body and free end portions

extended rearwardly into the chamber of the movable breech-block D and relatively over the step or projection P of the hammer I. 70 When the breech-block is in position, as shown in Fig. 1, the rearward and free end of said mainspring will have bearing on the upper side of the step or projection P of the hammer. When the breech-block D is being 75 swung downwardly and forwardly, so as to carry the movable breech-block down and out from the chamber of the receiver, the step P of the said hammer will be carried away from the free or rearward end of the said main- 80 spring Q. When the forward movement of said breech-block is continued, the upper projecting portion P' of the hammer will be carried against the free end of said mainspring and sets said hammer to half-cock. The 85 swinging movement of the breech-block being continued, the hammer will be carried free from said mainspring, and the lower side of the firing-pin holder D² will be carried to a bearing on the free end portion of said main- 90 spring, substantially as shown in Fig. 3, when the breech-block will be held suspended partly from said mainspring and partly from the pivot on which it swings, and the said mainspring Q will operate to balance the finger- 95 lever E and its attached movable breech D and hold them ready for their return from position shown in Fig. 3 to that shown in Fig. 1. In operating the finger-lever E for removal of its attached breech-block and for operating 100 the extractor, this mainspring operates as an elastic check or stop at finish of the movement of said breech-block by the bearing of the rear free-end portion of the said mainspring against the lower side of the firing-pin 105 holder D², as above described. The sear I' is held ready for engagement with the notches P P' of the hammer by suitable spring i.

K is the trigger for operating the sear I'. If preferred, the sear (as an independent 110 piece) may be omitted, and its portion engaging with the notches p p' of the hammer may be made integral with the trigger, in which case the spring i will have bearing on the trigger at any suitable point. 115

In Fig. 4 are shown double triggers. The fore set-trigger K has a rearward extension that can be made to act at will with the sear I' to operate the same for releasing the hammer, as does the single trigger shown in Fig. 1. 120 Made in this fore set-trigger is notch k, which receives the free end of spring k'. (Shown by full lines in Fig. 4 and by dotted lines in Fig. 14.) This fore set-trigger has also made with it lateral projection k², for engagement 125 with the forward end k³ of the arm of the rear set-trigger K'. The rear set-trigger K' is provided rearward of its pivot-pin with step l, which is relatively on a plane above its pivot-pin. 130

S is the main trigger-spring, which has made in its rearward half portion the central slot s, through which slot the horizontal arms of the double set-trigger work. The front

end of this spring is secured to a suitable trigger-plate T, which receives the pivots *t t* of said triggers. The rear free end of said spring S has bearing on the upper side of plate T when the forward end of the horizontal arm of the rear set-trigger K' is out of engagement with the fore set-trigger K. This free rear-end portion of the said spring is directly over the step or projection *l* of the rear set-trigger and has bearing on the same when the forward end of the arm of the rear set-trigger K' is in engagement with the projection *k* of the fore trigger K. When the hammer is set at full-cock and the sear I' is in engagement with the full-cock notch of the same and with its rear end in position for receiving the impulse from the arm of the rear set-trigger K', and a slight pressure of the fore trigger K will release the front end of the arm of the rear set-trigger K', and at the same time the spring S, pressing on the step or projection *l* of the rear set-trigger will give impulse to the forwardly-projected arm of the same and causes it to suddenly strike the rear end of the sear and disengage it from the full-cock notch of the hammer, when the mainspring actuating the hammer will throw it forward with sufficient force against the firing-pin V to cause it to explode the cartridge in the barrel.

The trigger-plate T is shown in Fig. 4 to have secured with it the double set-triggers and their respective actuating springs, and is also shown in said figure to be secured to the finger-lever E by means of a screw U, which also holds the springs S and *k*' in place for operation on the respective set-triggers.

Sunken in a side of the body of the hammer neighboring the half and full cock notches *p p'* (and in an area of the same which will include both said notches and extend past the same to a short distance) is the fly-seat *z*, having a circular head recess *z'* communicating with said recessed seat. This fly-seat *z* and its adjoining circular head-recess *z'* are sunken to a small and equal distance below the surface of the side they are made in.

Z is the fly, made substantially as shown, and having its lower end made with an acute angle and with an extension of length which will carry the angle of the lower and free end beyond the line of the curve of the portion of the hammer between the half and full cock notches *p p'*. Made with the body of this fly is the circular head Z', of size and form to fit in the circular recess *z'* in the hammer, so as to freely work in the same. This fly with its head end is made with a thickness corresponding with the depth of the seat and head recess. This form of construction of this fly and its seat obviates the employment of a hole through the hammer and a pintle-form pivot as heretofore employed.

After the hammer has been operated as above described to strike the firing-pin for exploding the cartridge, the operator will by

means of the finger-lever E swing the breech-block, with the portions of the lock secured therewith, downwardly and forwardly from position of full lines in Figs. 1, 4, and 7 to that of full lines in Fig. 3, and while said breech-block is being moved its full distance from position shown in Figs. 1 and 7 to that in full lines in Fig. 3 the several operating parts and elements above described, respectively, will be made to operate, as above described, for unclosing the rear end of the barrel, for effecting the removal of the shell from within the chamber of the same and introducing a new cartridge, and for setting the hammer at half (or full) cock preparatory to another firing of the arm. The pivoted lever or arm G obviates the use of a vise or other clamping device for aiding to revolve the barrel when it is to be screwed in or out of place in the receiver.

Having described my invention, what I claim, and desire to secure by Letters Patent, is—

1. The combination, with a receiver and a barrel secured thereto by a screw-thread, of a wrench lever or arm which is secured to said barrel by a pivot, whereby it may be turned from position about parallel with the lower side of said barrel to an angle with the same, substantially as and for the purposes set forth.

2. The combination, with a receiver and a barrel which is secured in place in the same by a screw-thread, of a lug connected with said barrel and a lever or arm pivoted with said lug and capable at will of being moved to a position about parallel with the lower side of said barrel and at an angle with the same, and vice versa, substantially as and for the purposes set forth.

3. The combination, with a receiver and a barrel which is secured therewith by a screw-thread, a lug connected to said barrel, and a lever or arm which can at will be set at an angle to said barrel for revolving the same and be changed to a position neighboring the lower side of said barrel, of the removable fore-arm provided with a recess which will receive said arm or lever when in position neighboring the lower side of the barrel, substantially as and for the purposes set forth.

4. The combination, with the barrel of a fire-arm and a receiver having in its forward end a recess *a*, of a piece which is pivoted with a lug connected with said barrel and which is extended to and serves as a button or locking device for engagement with the sides of the said recess of the receiver, substantially as and for the purposes set forth.

5. In a fire-arm, the combination, with the receiver having its forward end recessed and its barrel secured to said receiver, of a fore-arm provided with a fore-arm plate having tongues *h*, which engage in grooves *h'*, provided in the side portions of the receiver, substantially as and for the purposes set forth.

6. In a fire-arm, the combination, with the

receiver having a rigid connection with the barrel and having its forward end below the breech of the barrel recessed, and a movable breech-block carrying the parts of the lock 5 except the mainspring of the hammer, of the hammer-mainspring rigidly secured in the forward part of the said receiver with its free end having bearing on the forwardly-extended step of the hammer only when the breech-block is in place within the receiver, substantially as and for the purposes set forth.

7. The combination, with a receiver, a barrel having a rigid connection with said receiver, a hammer-mainspring secured in the forward portion of the said receiver with its free end projecting rearwardly in the chamber of a pivoted breech-block, of the hammer provided in its rear side with half and full cock notches and having with its front side a step for receiving the pressure of the mainspring for throwing the same forward, and provided with a projection above said step which will have bearing against the opposite side of the free end of the mainspring when 25 the breech-block is being thrown down from the receiver to throw the hammer to half or full cock, and the mechanism for holding the hammer to the place thrown by the said spring, substantially as and for the purposes 30 set forth.

8. The combination, with the receiver and the barrel secured thereto, of a breech-block pivoted to said receiver and finger-lever secured to said breech-block, the latter containing the parts of the lock (excepting the mainspring of the hammer) and also the socket or holder of the firing-pin, of a mainspring for operating with the hammer and which has its fixed end secured in a recess contained in the forward portion of the receiver and its rear free end for operating the hammer working within the chamber of the breech-block and also coacting with a pivot on which the breech-block turns to support and balance said breech-block and finger-lever when thrown down and out of the receiver, substantially as and for the purposes set forth.

9. The combination, with a breech-block which is pivoted to the receiver and contains 50 the firing-pin, hammer, and mechanism for releasing the hammer, of the hammer-mainspring having its forward end secured to the receiver into which the breech-block works and its rear end free for alternate bearing 55 against the forwardly-projecting step P for throwing the hammer forward against the firing-pin, and a projection P' or P² on the plane above for throwing the hammer back to half-cock or full-cock, substantially as and 60 for the purposes set forth.

10. The combination, with the receiver provided with inclines c at its rear end, of the chambered movable breech-block containing the parts of the lock and having with its rear 65 end the incline e for coaction with incline c, and provision for the forward movement of said movable breech-block when being thrown

down for the passage of its incline e from out of engagement with the incline c, substantially as and for the purposes set forth.

11. The combination, with the chambered receiver and a pivot-pin secured in its forward portion and having in its rearward portion one or more inclines c', of the movable breech-block pivoted on said pivot-pin, with provision for its forward movement in relation to the receiver when being turned down and forward from the chamber of the same, and having one or more inclines e' for coaction with the incline or inclines c' of said receiver, substantially as and for the purposes set forth.

12. The combination, with a chambered receiver having a barrel rigidly secured to its forward end and having one or more inclines, 85 as c c', in its rearward portion of chamber and a fixed pivot-pin in the forward portion of the same, of the movable breech-block containing the principal portions of the lock and provided with one or more inclines for coaction 90 with the incline or inclines made with the rear portions of the chamber of the receiver and an oblong pivot-hole receiving the said fixed pivot-pin, substantially as and for the purposes set forth.

13. The combination, with the chambered receiver having secured with it the barrel and provided with one or more inclines c or c' in its rearward portion, and a pivot-pin in the forward portion of said chamber, of a breech-block pivoted by an oblong pivot-hole in its forward end on said pivot-pin and having one or more inclines for coaction with said inclines of said receiver, and provision for forcing the said breech-block rearwardly when it is in place in the chamber of said receiver, substantially as and for the purposes set forth.

14. The combination, with the chambered receiver having one or more inclines c c' in its rearward portion and a fixed pivot-pin 110 passing through the forward end portion of its chamber, and a breech-block carrying the main parts of the lock and having with its rear end portion one or more inclines for coaction with the incline or inclines of the receiver and in its forward end an oblong pivot-hole which receives the said fixed pivot-pin, of an elastic keeper which has bearing on the forward end of said breech-block when it is in place within the chamber of the receiver and is out of engagement with said breech-block when the latter is thrown downward or forward, substantially as and for the purposes set forth.

15. The combination, with a breech-block 125 which is secured with a chambered receiver by a fixed pivot which works in an oblong pivot-hole made in the forward end of the said breech-block and has one or more inclines which hold with the corresponding inclines made in the rear end of said receiver and which coact to give to the said breech-block a forward and endwise movement when it is being moved down and out from the cham-

ber of the said receiver, of a yielding keeper applied to the forward end of the breech-block and holding with the same while the inclines of the breech-bolt and receiver are coacting, 5 substantially as and for the purposes set forth.

16. The combination, with a receiver having fixed in the forward portion of its chamber a pivot-pin and provided at its rear end with one or more inclines $c c'$ and a movable 10 breech-block containing the principal portions of the parts of the lock and provided in its rear end portion with one or more inclines for coaction with the said inclines of the said receiver and having in its forward end portion an oblong pivot-hole which receives the 15 said fixed pivot-pin and also in its forward portion the recess a' , made in its side and neighboring its oblong pivot-hole, of a piece pivoted on said pivot-pin and capable of entering the said recess a' when the breech-block has been moved to position downward and forward, so that the rearward portion of its 20 oblong pivot-hole will receive the fixed pivot-pin, substantially as and for the purposes set 25 forth.

17. The combination, with a chambered receiver and a barrel rigidly secured to the same and a pivot-pin secured in the chamber of the receiver at a point relatively at or near 30 and below the rear end of the said barrel, of a breech-block working within said chamber and containing the principal parts of the lock and pivoted by its forward end with the said pivot-pin and means for moving said breech-block out of and away from the chamber of the 35 said receiver, and the extractor pivoted also on the said pivot-pin and provided with a step or projection for engagement with the movable breech-block when it is being moved 40 downwardly and forwardly from said receiver, substantially as and for the purposes set forth.

18. The combination, with the breech-block which is pivoted within a chambered receiver at a point relatively below the rear end of a 45 barrel which is secured to the said receiver, of an extractor which is pivoted to the pivot-pin on which the breech-lock turns and is provided with a step or projection which can be brought into action with the forward portion 50 of the breech-block when the firing-pin holder D^2 has been moved away from the open end of the breech of the barrel and before the breech-block has been moved to its full distance downward and forward, substantially 55 as and for the purposes set forth.

19. The combination, with a breech-block which is pivoted within the chamber of the receiver by a pivot-pin which is located relatively at the rear end of the breech of the 60 barrel and below the same and is provided with a recess a made neighboring its oblong pivot-hole, of the extractor provided with projections $o o'$, and also pivoted on the said pivot-pin, and a lever secured to said breech-block, substantially as and for the purposes 65 set forth.

20. The combination, with a chambered re-

ceiver having the barrel secured thereto and provided with one or more inclines $c c'$ at the end of its chamber, of a breech-block having 70 with its rear end corresponding inclines and containing the principal parts of the lock and provided in its forward end with an oblong pivot-hole which receives the pivot on which said breech-block swings, and an extractor 75 which will become engaged with the said breech-block when the latter has been moved downward and forward so that its oblong pivot-hole receives in its rearward portion the pivot-pin, substantially as and for the purposes set forth.

21. The combination of the breech-block provided in its rear end with one or more inclines $e e'$ and having located in its forward end an oblong pivot-hole from which it swings 85 by a pivot-pin which is contained within a receiver having corresponding inclines and also provided on its forward end with the incline n , which will have bearing against the keeper when the said breech-block is in place within 90 the chamber of the receiver and also have bearing against the lower side of the socket C' receiving the barrel when said breech-block is turned fully downward and forward, substantially as and for the purposes set forth. 95

22. The combination, with the socket portion of the receiver to which the barrel is secured, of the hammer-mainspring, and a binding-screw holding the fixed end of said spring firmly secured to said socket and its free end 100 portion within the chamber of the movable breech-block which contains the other parts of the lock, substantially as and for the purposes set forth.

23. The combination, with a hammer provided with half and full cock notches and having in it a fly-seat which is sunken in one of its sides to a small distance from the side surfaces thereof, having a circular form of head-seat communicating with the said fly-seat, of the fly having a circular head with thickness corresponding with the body of the fly and a form corresponding with a circular head-seat and capable of free movement from half-cock notch to full-cock notch and the 115 reverse in relation to the movement of said seat when said hammer is moved, substantially as and for the purposes set forth.

24. The combination, with a receiver having a barrel secured therewith, of a breech-block 120 pivoted within the chamber of said receiver and containing the hammer and sear, a finger-lever, a trigger, and a hammer-mainspring which has its forward end secured with the receiver and its rear free end bearing on a 125 forwardly-projected step of the hammer when the breech-block is in place in the receiver, substantially as and for the purposes set forth.

25. The combination, with a trigger-plate and double set-triggers pivoted therewith with provision for the rear set-trigger being locked at will with the front set-trigger, of the slotted horizontal rear trigger-spring having its forward end secured to the trigger-plate, its slot 130

receiving the horizontal arms of the triggers and its rear end bearing on the step or projection which is relatively rearward of the rear set-trigger, substantially as and for the 5 purposes set forth.

26. The combination, with a trigger-plate having double set-triggers pivoted therewith, the front set-trigger being provided with a notch relatively forward of its pivot and the 10 rear set-trigger with a projection or step which is relatively rearward of its pivot and provision for locking the forward limb of the rear set-trigger with the front set-trigger, of a spring secured to the forward part of the 15 trigger-plate with its free end working in a notch made in the front set-trigger and a horizontal slotted mainspring also secured to the front portion of the trigger-plate with its slot receiving the horizontal arms of both set- 20 triggers and its rear end having bearing on the step or projection on the rear set-trigger, substantially as and for the purposes set forth.

27. The combination, with a finger-lever connected with a trigger-plate having double set-triggers pivoted therewith, a slotted main-spring arranged on the upper side of said trigger-plate and relatively parallel with the same, the horizontal limbs of both triggers working through the slot thereof and its rear- 25 ward end bearing on a projection or step made with a rear side of the rear set-trigger, of a breech-block pivoted to a receiver and secured to said finger-lever and containing a hammer and sear, and the hammer-main- 30 spring secured in the receiver forward of the hammer, substantially as and for the purposes 35 set forth.

EUGENE PRINGLE.
